UNITED STATES PATENT OFFICE.

CHARLES J. HOLUB, OF CHICAGO, ILLINOIS.

ADJUSTABLE STOVEPIPE-JOINT.

No. 839,148.

Specification of Letters Patent.

Patented Dec. 25, 1906.

Application filed November 11, 1905. Serial No. 286,863.

To all whom it may concern:

Be it known that I, CHARLES J. HOLUB, a citizen of the United States, residing at Chicago, in the county of Cook and State of Illinois, have invented certain new and useful Improvements in Adjustable Stovepipe-Joints, of which the following is a specification.

My present invention relates to improvements in adjustable stovepipe-joints, and has special reference to the provision of a joint whereby a stove can be quickly and conveniently connected with the flue without the necessity of cutting a section of stove-piping to secure the proper length, which is now almost universally necessary.

At present stovepipe can only be purchased upon the market in sections of a certain length. It very rarely happens that the distance between the stove and the flue-hole in the wall can be made up of these sections without cutting one of them. To cut a section of stovepiping to make up a stovepipe of the desired length requires a tinner provided with the tools of his trade. With my adjustable stovepipe-joint any one can adjust and secure the joint and make up a stovepipe of any desired length without any tools whatever.

It has been found by the dealers to be impracticable to carry stovepipe-sections of varying lengths, because of the immense diversity of lengths which would be required. My adjustable stovepipe-joint can be manufactured in a factory in large numbers at a greatly-reduced cost and supplied to a consumer for less than he could have an ordinary section cut to the proper length.

My invention consists of a new and improved construction and combination of parts, as will presently appear.

In the accompanying drawings, Figure 1 is a view of the two members of my device in a position to be adjusted with a portion of one member broken away to show the locking tongue or tang. Fig. 2 is a view of the two members of my device in a locked position with a portion of one member broken away, showing the locking tongue or tang in engagement with the locking means upon the other member. Fig. 3 is a sectional view taken through the line X-X, Fig. 2. Fig. 4 is a sectional view the same as Fig. 3, except that the locking means are reversed and the interior member carries the locking tongue or tang. Fig. 5 is a sectional view

the same as Fig. 3, except that the function of the locking tongue or tang is secured by a depressed segment in the end of the exterior member.

In the drawings the numeral 1 represents one member of my device, which is an ordinary piece of stovepipe. The numeral 2 represents the other member, which is also a piece of stovepipe, but with a smaller diameter than member 1, so that member 2 can be easily pressed into or drawn out of member 1. The ordinary stovepipe which is sold upon the market consists of a sheet or blank of metal the lateral edges of which are bent into reverse hooks assembled and pressed, or what is technically known as "seamed," closely together. This construction produces four thicknesses of metal at the seam, with the incident thickening and strengthening of the pipe at that portion. I locate the lock or means for maintaining my joint at the desired length upon these seams.

At one end and upon the inner surface of the member 1, I attach the tongue or tang 3 by means of the rivet 4. The tongue or tang 3 is bent so as to spring out slightly from the surface of the member 1, while at the same time being easily depressed to contact with the surface for the purpose of inserting the member 2. The outer thickness of the seam of the member 2 I slit or cut transversely and pry up or distend the metal at one side of said slits or cuts to form the shoulders or pockets 5, as clearly shown in Figs. 1, 2, 3, 4 and 5. To adjust my joint, insert member 2 into member 1, twist the respective members to a position, as shown in Fig. 1, where the locking devices carried by the respective members are not in line, press member 2 into member 1 until the desired length of section is secured, rotate the respective members until the locking devices carried by the respective members are in line, as shown in Fig. 2, when the tongue or tang 3 will engage a shoulder or pocket 5 and lock the joint against compression.

Fig. 4 illustrates a modification of my invention in which the interior of member 1 is cut and shouldered, and member 2 carries upon its outer surface the tongue or tang 3. Fig. 5 illustrates another modification of my invention wherein the tongue or tang 3 is dispensed with and a segment of member 1 depressed at 6 to engage the shoulder 5.

From the foregoing description, taken in connection with the drawings, it is evident

that I provide an extremely simple stovepipe joint or section which is susceptible to adjustment to various lengths and which can be readily manipulated without the use of tools or other means except the hands.

What I claim as new, and desire to secure by Letters Patent, is—

1. An adjustable stovepipe-joint consisting of two sections of stovepiping, one of said sections telescoping into the other, the surface layer of metal upon the seam of one of said sections being cut at intervals, the metal at one side of said cuts being raised to provide pockets and means carried by the other of said sections to engage the desired one of said pockets.

2. An adjustable sheet-metal-pipe joint

consisting of two telescoping sections of sheet-metal piping the lateral joint or seam of said sections being formed by the engagement of reversed bends in the metal of the sections, the surface thickness of the seam upon one of said sections being transversely cut and the metal at one side of said cut being raised to form a pocket and means carried by the other of said sections to engage said pocket.

In testimony whereof I affix my signature in presence of two witnesses.

CHARLES J. HOLUB.
